US0D1083436S

(12) United States Design Patent (10) Patent No.: US D1,083,436 S
(45) Date of Patent: * Jul. 15, 2025

(54) STORAGE RACK

(71) Applicant: Zhuhai Pristar Technology Co., Ltd.,
Zhuhai (CN)

(72) Inventor: Jinpei Li, Zhuhai (CN)

(73) Assignee: ZHUHAI PRISTAR TECHNOLOGY
CO., LTD., Zhuhai (CN)

(*) Notice: Patent file contains an affidavit/declaration under 37 CFR 1.130(b).

() Term: 15 Years

(21) Appl. No.: 29/880,293

(22) Filed: Jul. 20, 2023

(30) Foreign Application Priority Data

Jul. 12, 2023 (CN) 202330434521.8
